UNITED STATES PATENT OFFICE.

JOSEPH E. BENJAMIN, OF NEAR REYNOLDS, NEBRASKA.

SPRING BED-BOTTOM.

SPECIFICATION forming part of Letters Patent No. 373,513, dated November 22, 1887.

Application filed August 20, 1887. Serial No. 247,449. (No model.)

To all whom it may concern:

Be it known that I, JOSEPH E. BENJAMIN, a citizen of the United States, residing near Reynolds, in the county of Thayer and State 5 of Nebraska, have invented certain new and useful Improvements in Spring Bed-Bottoms; and I do declare the following to be a full, clear, and exact description of the invention, such as will enable others skilled in the art to 10 to which it appertains to make and use the same, reference being had to the accompanying drawings, and to the letters and figures of reference marked thereon, which form a part of this specification.

15 This invention relates to bed-bottoms, and has for its object the construction of a bed-bottom of fabric which will not sag or tilt to one side when the weight is placed near the edge.

20 The improvement consists in having said bottom of fabric re-enforced by lever or levers which are pivotally supported at one end and have springs supporting their other ends, said springs being vertically adjustable to regulate 25 the resistance of the lever or levers to the load placed thereon.

20 The improvement further consists in the novel construction and arrangement of parts, which will be more fully hereinafter set forth 30 and claimed, and shown in the annexed drawings, in which—

35 Figure 1 is a perspective view of a bed-bottom embodying my invention; Fig. 2, a vertical longitudinal section on the line X X of Fig. 1; Fig. 3, a detail perspective view showing the means for adjusting the fulcrum or pivotal support of the lever, and Fig. 4 a plan view of a modified form.

40 The frame of the bed is composed of the head and foot sections A and B and the side rails, C, respectively. The fabric D is stretched between the cross-bars E and F, and its edges are free. The cross-bar F has journals f at each end, which enter openings in the inner 45 ends of the bolts G, seated in the side rails. The outer ends of the bolts are threaded and pass through the head-section A and receive the nuts g, by which the bolts are drawn out when it is desired to increase the tension of 50 the fabric.

The lever J is secured at one end to the

cross-bar F, and is supported at its other end on the spiral spring K, which rests on the bar L, adjustably supported by the frame. The plates M, secured to the ends of the bar L, 55 have vertical slots m, and through these slots pass set-screws m', which enter the side rails and hold the bar at any desired position.

Instead of a single lever, as shown in Fig. 1, which is centrally disposed, there may be a greater number, which may be differently arranged, as shown in Fig. 4, which shows four levers, one lever being located at each corner, and the levers at one end extend toward the levers at the opposite end of the bed-bottom. 65 These levers J' will be supported at one of their ends on springs, and at their opposite ends in a manner similar to lever J. The free end or ends of the levers bear upward against the fabric, D, of the bottom with a greater 70 or less force, according to the tension of the springs which support them, which tension can be regulated by moving the bar carrying the springs up or down, as previously intimated.

By having the lever or levers arranged beneath the top D of the bed said top is re-enforced and prevented from sagging, as part of the load is sustained by the lever. Furthermore, as the lever yields under the load placed thereon the said top slackens and accommodates 80 itself to the form of the load, and permits the greater portion of the load to be sustained by the lever. The lever likewise prevents any undue straining of the fabric or wire top incident to a person jumping thereon by cushioning 85 the force of the shock.

Having thus described my invention, what I claim, and desire to secure by Letters Patent, is—

1. A bed-bottom composed of a frame, a fabric stretched over said frame, a lever located beneath the fabric and journaled at its outer end, and having its inner end bearing against the fabric, the spring for supporting the inner end of the lever, the bar L, the slotted plates M, and the set-screws m', substantially as and for the purpose described.

2. The combination, with the frame, the bar located at one end and adjustable lengthwise of the frame, and the fabric secured at its ends to said cross-bar and the opposite end of the frame, of the lever secured at one end to the

aforesaid cross-bar, the spring, and the adjustable bar carrying said spring, substantially as described.

3. The combination of the frame, the bar F, having journals at each end, the bolts G, forming bearings for the journals and threaded on their outer ends, the nuts g, the fabric connected at one end with bar F, and at its other end with the frame, the lever fastened at its inner end to the bar F, the spring, and the

supporting-bar L, adjustably connected with the frame, substantially as and for the purpose described.

In testimony whereof I affix my signature in presence of two witnesses.

JOSEPH E. BENJAMIN.
